Primary Examiner—Doris V. Coles*Assistant Examiner*—Catherine R. Oliver*Attorney, Agent, or Firm*—Brown, Martin, Haller & McClain**CLAIM**

The ornamental design for a surfboard shoulder harness, as shown.

DESCRIPTION

FIG. 1 is a perspective view of a surfboard shoulder harness showing our new design;

FIG. 2 is a perspective view with part of the strap shown broken away for convenience of illustration; and,

FIG. 3 is a perspective view, from the opposite side thereof, with part of the strap shown broken away for convenience of illustration.

The dotted line showing of a surfboard in FIG. 1 is for illustrative purposes only and forms no part of the claimed design.
